MACHINE FOR PUNCHING JACQUARD CARDS

Hans Ghilardi, Arben, Switzerland, assignor to
 Societe Anonyme Adolphe Saurer, Arben, Switzerland, a corporation of Switzerland

Application February 17, 1933, Serial No. 657,254
 In Germany February 23, 1932

3 Claims. (Cl. 164—114)

In the operation of machines for punching jacquard cards for subsequent use in automatic embroidering machines an enlarged pattern of the design to be reproduced is mounted upon the

5 pattern board of the pantograph mechanism. The design of the pattern is then traced by the stylus of the pantograph mechanism and the movements of the stylus are transmitted through suitable operating connections, such as rack bars, 10 and gears, to the control devices, such as drums, of the punching mechanism, proper provision being made for the reduction in scale which is to be accomplished in the design as reproduced on the embroidering machine. It has been proposed heretofore so to arrange the transmission members between the pantograph mechanism and the control mechanism that the ratio of translation may be changed, this having been 15 accomplished through the coupling of the connections at different points so that they may be lengthened or shortened as required. This arrangement has the disadvantage that in each instance of change the individual parts must first be disengaged and then reengaged in the 20 changed ratio of translation.

In accordance with the present invention the transmission devices between the movable parts of the pantograph mechanism and the control device of the punching mechanism embody a 25 controllable change wheel gearing comprising a plurality of change gear sets of different ratio one or another of which can be brought into operative relation through a single manual control device at the will of the operator. It is therefore necessary only to bring one of such gear sets of one ratio into operative relation in place of another of different ratio when a pattern of a 30 different scale is to be substituted for one previously used or when a change in reduction ratio, as between the pattern and the embroidery, is to be effected. If there is to be associated with the pattern mechanism and the punching mechanism a control embroidering machine on which, for purposes of checking errors and the like, a 35 single unit of the design is produced on the desired scale, similar gearing, comprising a plurality of change gear sets may be incorporated in the transmission mechanism between the pantograph mechanism and such control embroidering machine so that the frame of the control 40 embroidering machine may be shifted in correspondence with the movement of the pantograph stylus and in accord with the punching of the jacquard cards, and the change gears may be 45 so mounted on the forwardly extending ends of

these shafts as to be readily removable. The invention will be more fully explained herein-after with reference to the accompanying drawings in which it is illustrated, and in which:

Figure 1 is a view in front elevation of a 5 pantograph mechanism constructed in accordance with the invention and a portion of a control embroidering machine, with the interposed and interconnected transmission devices.

Figure 2 is a view of the same in sectional 10 elevation on the plane indicated by the broken line A—B of Figure 1 as seen from the left hand.

Figure 3 is a view of the pantograph mechanism and the transmission devices as seen from 15 above in Figure 1.

Figure 4 is a view in front elevation, on a scale somewhat larger than Figure 1, showing a portion 20 of a pantograph mechanism, a portion of the control embroidering machine and the interposed transmission devices.

Figures 5 and 6 are detail views, on a larger 25 scale, of the device shown at the right hand end of Figures 1 and 3 and shown also in Figure 2, of a device for adjusting the pattern board of the pantograph mechanism.

Figures 7 and 8 are detail views of portions of 30 the transmitting members to be referred to.

Figures 9 and 10 are views, respectively, in 35 vertical section and in horizontal section and on a larger scale, of devices directly concerned in the positioning of the control drums of the punching mechanism.

Figures 11 and 12 are detail views in section, respectively, on the plane indicated by the lines 40 C—D and E—F of Figure 9.

Figure 13 is a detail view in sectional elevation, in a plane parallel to that of Figure 1, of the 45 punching mechanism.

In the drawings the pantograph mechanism is indicated generally at P, the punching mechanism at K, and the control embroidering machine at S, these several mechanisms being operatively connected as will be explained.

The pantograph mechanism P is provided with a pattern board 1 to which the design 2 to be 45 reproduced is secured, the pattern board being so mounted in the standards 3 as to be adjustable up and down. For the purpose of adjustment it is provided on its rear side with rack bars 4 engaged by gear segments 5 on a shaft 6 rotatably mounted in the standards. At one end, as at the right hand end in Figures 1 and 3, the shaft 6 is provided with a manual lever 7 (shown also in detail in Figures 5 and 6) provided with a spring actuated latch 8 and movable over a 50

stop disc 9 fixedly mounted on the adjacent standard. The disc 9 is formed with notches 10, 10^a, 10^b and 10^c with one or the other of which the latch 8 may be engaged when the lever 7 is turned. Through such rotation of the shaft 6 and the gears 5 the pattern board 1 may be raised or lowered into different adjusted positions determined by the stops 10, 10^a, etc.

In front of the pattern board 1 are two parallel, horizontal but vertically movable tracks 11, 11^a, spaced apart at their ends by vertical members and supported by belts 12, carried at each end of the pantograph mechanism by sheaves 13 and 13^a. The upper sheaves 13 are connected 15 with each other through a shaft 14 and the lower sheaves 13^a through a shaft 14^a, so that equal movement of the sheaves and parallel movement of the tracks along the entire surface of the pattern board in vertical direction are assured. 20 Rollers 15 carried by the end members 15^a run on corresponding tracks of the standards 3. Also in front of the pattern board are two parallel, vertical tracks 16 and 16^a held together and spaced apart by spacing members 17, 17^a, provided, respectively, with rollers 18 which run on 25 horizontal, fixed guide rails 19 of the pantograph mechanism. A stylus supporting frame, supporting the stylus 22, is provided with rollers 20, which travel on the vertical tracks 16, 16^a, and 30 with rollers 21 which travel on the horizontal tracks 11, 11^a. The stylus, which may be grasped by the hand of the operator, is therefore freely movable by the operator either in a vertical direction or in a horizontal direction, or simultaneously in both vertical and horizontal directions, 35 whereby the pattern on the pattern board may be traced by the point of the stylus. It will be understood that the horizontal frame constituted by the tracks 11, 11^a with the members 15^a and 40 the frame constituted by the tracks 16, 16^a with the members 17 are moved respectively in a vertical direction and in a horizontal direction with the stylus. Such movements of the two frames are transmitted, as hereinafter explained, to the 45 control devices of the punching mechanism K and to the control embroidering mechanism S.

In the embodiment of the invention illustrated in the drawings the control devices of the punching mechanism consists of four perforated drums 50 23^a, 23^b, 23^c, 23^d, shown particularly in Figures 5, 9, 10 and 13, the drums 23^a and 23^b moving with the frame 11, 11^a, 15^a, as it is shifted vertically with the pantograph stylus, while the drums 23^c and 23^d move with the frame 16, 16^a, 17 and 55 with the pantograph stylus as it is shifted horizontally. At each vertical movement of the frame 11, 11^a, 15^a and at each horizontal movement of the frame 16, 16^a, 17 the drums 23^a and 23^b or the drums 23^c and 23^d, as the case may 60 be, are shifted rotatably, bringing into line with the needles 25 of the punching mechanism either perforations or unperforated portions. The punching mechanism of itself is constructed and arranged to operate in usual and well known manner, substantially as shown and described in Letters Patent of the United States No. 1,118,481, dated November 24, 1914, issued to the assignee herein as the assignee of Karl Eggart, and therefore is not shown or described in detail herein. 65 When the perforated drums, as for example, the drums 23^c and 23^d as shown in Figure 13, have been rotated by a movement of the stylus, so that the proper holes therein are brought into alignment with the needles 25 at each end, the carrier 24^a is moved in one direction toward the 70

drum 23^c and in the opposite direction toward the drum 23^d and is then restored to normal position, substantially as described in said Letters Patent No. 1,118,481. In this movement of the carrier 24^a certain of the needles 25^a are shifted in one direction or the other with respect to the carrier 24^a by reason of the contact with unperforated portions of the drums, while others of the needles, which enter the perforations, suffer no change of position with respect to the carrier. 10 It will be understood that the needle bodies 24 are frictionally mounted in the carrier and may therefore be shifted with respect thereto as may be determined by the rotary movement of the drums under the influence of the stylus. The 15 effect of such action is to place certain of the needles with the projections 32 of the bodies 24 in line with the heads 31 of the corresponding punches 28. At this time all of the needles have been withdrawn from the perforations of the 20 drums so that when the block 27 is moved downward, as by the oscillating arm 27^a, acting in timed relation with other parts of the mechanism, the punches with which the projections 32 are then in alignment are moved down and caused 25 to punch the jacquard card 30. It will be understood that each stitch movement of the pantograph stylus, consisting of a vertical component and a horizontal component is thus transferred to the card in the form of two perforations, one 30 at each side of the card, and that the jacquard card, when placed in the automatic embroidering machine, causes a corresponding stitch movement of the embroidery frame of such machine in such ratio to the movement of the pantograph stylus as has been predetermined. 35

The shifting of the control drums 23^a, 23^b, 23^c and 23^d of the punching mechanism is effected through the instrumentalities now to be described. brought into operative relation at the will of the operator.

The shaft 34, at its other end, has secured to it a large gear 45 which meshes with gears 46 and 46^a, mounted rotatably on fixed shafts 47 and 47^a respectively. The control drums 23^a, 23^b, 23^c, 23^d are also mounted rotatably on fixed shafts 47 and 47^a, as shown in Figure 10. As usual in punching mechanisms of the character indicated, the corresponding control drums 23^c and 23^d can be coupled selectively with the respective gears 46 and 46^a through suitable coupling devices 48 and 48^a. Thereby the horizontal component movement of the pantograph stylus is selectively transmitted in the determined ratio through the shaft 34, the gear 35 and on one or the other of the gears 46, 46^a to the drum 23^c or the drum 23^d. In a similar manner the vertical component of the movement of the pantograph stylus is selectively transmitted, in the desired ratio, to the drum 23^a or the drum 23^b, which are also mounted loosely on the fixed shafts 47 and 47^a and can be coupled, through the respective coupling devices 63 and 63^a, with the gears 62 and 62^a respectively. To effect this the movement of the horizontal but vertically movable frame 11, 11^a, 15^a of the pantograph mechanism is transmitted through a vertical rack bar 49 (Figures 1, 2, 4, 11 and 13) carried by the belt 12 at the left hand of the pantograph mechanism to transmission gearing, shown generally at G² in Figures 2, 9, 10, 11 and 13, and thence to a tubular housing or sleeve shaft 50 which encloses the shaft 34. The transmission gearing G² comprises two gears 51 and 52, the hubs 54 of which are formed with annular grooves 53 for engagement by the studs 55 of a lever g² shiftable in a vertical plane on an axis 56. By shifting the lever g² from one position to the other either the gear 51 or the gear 52 may be brought into engagement with the rack bar 49. The gear 51 is splined on the sleeve shaft 50 so as to rotate therewith but to be capable of axial movement, while the gear 52 is splined on a rotatable shaft 57 which carries a large gear 58 meshing with an intermediate gear 59 which in turn meshes with a gear 60 on the sleeve shaft 50. A large gear 61 on the sleeve shaft 50 meshes with gears 62, 62^a, which are mounted loosely on the shafts 47, 47^a respectively and may be coupled respectively with the control drums 23^b and 23^a through suitable coupling devices 63 and 63^a respectively. The drums 23^d and 23^a are thus selectively rotated, at the desired gear ratio, in accord with the vertical components of movement of the pantograph stylus.

It will be understood that the gear ratios of the gearings G¹ and G² thus interposed in the transmission devices between the pantograph stylus and the control drums of the punching mechanism must be such that the movements of the rack bars 33 and 49 will be transmitted to the control drums in the desired ratios, change being made from gears of one ratio to the gears of the other ratio by the shifting of the levers g¹, g² according to the reduction to be effected between the pattern design and the design as reproduced on the embroidering machine.

It is usual, in shops in which the movements of the embroidery frames are controlled by a jacquard card, to provide in operative relation with each punching mechanism and the corresponding pantograph mechanism a small embroidering machine (indicated generally at S in Figure 1) in order that the operator may be able to see before him a specimen of the embroidery

produced under the control of the punching mechanism. It will be understood that the embroidery frame of such control embroidering machine must be moved in exact correspondence with the transmission ratio between the pantograph mechanism and the punching mechanism in both vertical and horizontal directions. At the left hand end of Figures 1, and on a somewhat larger scale in Figure 4 and with the omission of parts which would obscure, there is shown a sufficient portion of such a control embroidering machine as is necessary to enable the operative connections to be illustrated sufficiently for the purposes of this application. Connected with the vertically movable frame 11, 11^a of the pantograph mechanism, as by brackets 64, is a rack bar 65 which may be brought into engagement with change wheel gearing G³ (Figures 4 and 7) adapted to transmit the vertical components of the movements of the pantograph stylus in the reduced ratio to a shaft 66 on which are gears 67 (one of which is shown in Figure 4) for engagement with rack bars 68 which carry the embroidery frame of the control or specimen embroidering machine. In like manner the horizontal components of the movements of the pantograph stylus are transmitted by a rod 71 (Figure 1), of which a rack bar 72 forms a continuation, through change wheel gearing, shown at G⁴ in Figures 1 and 4. The movements of the rack bar 72 are transmitted, in the desired reduction ratio, through shaft 73, gear 75 and horizontal rack bar 74, direct to the embroidery frame 76 to effect the horizontal movements thereof, the frame 76 being guided by rollers 77 in the frame 63 which is guided by rollers 70, bearing on the standards of the machine for vertical movement.

It will be understood that the change wheel gearing G³ and the change wheel gearing G⁴ are constructed and arranged to operate as already described with respect to the change wheel gearings G¹ and G² under the control of the manual levers g³ and g⁴, the change of reduction ratio being effected as to the control embroidering machine by the proper shifting of the levers g³, g⁴ and as to the punching mechanism by the shifting of the levers g¹, g². Detail description of the change wheel gearings G³ and G⁴ is unnecessary. It will be understood that shifting of the embroidery frame of the control embroidering machine, with consequent adjustment of the punching mechanism, necessitates also a corresponding shifting of the pattern board 1 of the pantograph mechanism. Such shifting is effected, as already described, through the operation of the manual lever 7, the board being secured in its new position through engagement of the latch 8 with the disc 9.

It will also be understood that in the operation of the mechanism when a perforation is to be made in the fabric to be embroidered the pattern board 1 is raised according to the selected enlargement by 120 mm., or 60 mm., for example. The pantograph stylus being moved across the face of the pattern, the path of such movement is translated to the card to be punched. When the perforation of the material has been completed the pattern board and the stylus are returned to their original positions, the path of the stylus being translated to the jacquard card. The control disc 9 is so formed that it may be placed in engagement in correspondence with the translation of the design to be reproduced, being pro-

vided with notches which correspond respectively in position with the reduction of the design.

It will be understood that various changes in details of construction and arrangement can be made without departing from the spirit of the invention as the same is defined in the accompanying claims.

I claim as my invention:

- 10 1. In a machine for punching jacquard cards, the combination of a pantograph mechanism, a card punching mechanism, a control embroidering machine, operative connections between the pantograph mechanism and the punching mechanism, operative connections between the control 15 embroidering machine and the punching mechanism, said connections including change wheel gearing comprising a plurality of change gear sets and manual devices whereby the change wheel gearing is shifted in accordance with the desired reduction ratio between the pattern and the punching mechanism, and operative connections between the pantograph mechanism and the control embroidering machine.
- 20 2. In a machine for punching jacquard cards, the combination of a pantograph mechanism including a horizontally movable member, a card punching mechanism, and operative connections between the pantograph mechanism and the punching mechanism, said connections including 25 a rack bar carried by and movable with the horizontally movable member of the pantograph mechanism, a driving shaft having its end extending forward of its bearings into the vertical longitudinal plane of the rack bar, a readily removable gear on said forwardly extending end
- 30 30 3. In a machine for punching jacquard cards, the combination of a pantograph mechanism including a horizontally movable member, a card punching mechanism, and operative connections between the pantograph mechanism and the punching mechanism, said connections including 35 a rack bar carried by and movable with the horizontally movable member of the pantograph mechanism, a driving shaft having its end extending forward of its bearings into the vertical longitudinal plane of the rack bar, a readily removable gear on said forwardly extending end movable into mesh with the rack bar, an auxiliary shaft parallel with the driving shaft and operatively connected therewith having its end extending forward of its bearings into the vertical longitudinal plane of the rack bar, a readily removable gear on said free end of the auxiliary shaft movable into and out of mesh with the rack bar and manually operated means for moving the gear on one shaft into and the other out of mesh with the rack bar.

movable into mesh with the rack bar, an auxiliary shaft parallel with the driving shaft and operatively connected therewith having its end extending forward of its bearings into the vertical longitudinal plane of the rack bar, a readily removable gear on said free end of the auxiliary shaft movable into and out of mesh with the rack bar and manually operated means for moving the gear on one shaft into and the other out of mesh with the rack bar.

3. In a machine for punching jacquard cards, the combination of a pantograph mechanism including a horizontally movable member, a card punching mechanism, and operative connections between the pantograph mechanism and the punching mechanism, said connections including a rack bar carried by and movable with the horizontally movable member of the pantograph mechanism, a driving shaft having its end extending forward of its bearings into the vertical longitudinal plane of the rack bar, a readily removable gear on said forwardly extending end movable into mesh with the rack bar, an auxiliary shaft parallel with the driving shaft and operatively connected therewith having its end extending forward of its bearings into the vertical longitudinal plane of the rack bar, a readily removable gear on said free end of the auxiliary shaft movable into and out of mesh with the rack bar and manually operated means for moving the gear on one shaft into and the other out of mesh with the rack bar, the operative connection between the two shafts consisting of gears carried on the shafts forward of the bearings.

HANS GHILARDI. 35
